CLOTHESLINE STRUCTURE

Mary E. Seymour, Union, Star, Mo.

Application February 6, 1947, Serial No. 726,905

1. Claim. (Cl. 211—119.13)

1

This invention herein disclosed relates to a pinless clothes line structure, and has for its principal object, first, a plurality of twisted lines horizontally positioned, second, a means to separate the lines temporarily for the insertion of the corners of pieces of laundry as attaching means for the laundry to the line without the use of clothes pins, and third, an efficient means to twist the lines and adjustably stretch the same to avoid sagging thereof.

A further object is to provide an element through which the lines are threaded, said element being the means to separate the lines from each other a spaced distance from each side thereof for attaching and removal of pieces of laundry from the lines as the element is moved manually a selected direction therealong.

A still further object is the provision of a rectangular frame that is stationarily retained by gripping the same, and an annular ring-like element to rotate in said rectangular frame for opening and closing the twists of the lines, said rectangular frame having a roller in each corner thereof to carry and permit free rotation of the ring-like element, last said object setting out the components of the line separating means above set forth.

These and other objects will hereinafter be more fully explained, reference being had to the accompanying drawings forming a part of this specification, and in which like characters will apply to like parts in the different views.

Referring to the drawings:

Fig. 1 is a side elevation of the clothes line structure.

Fig. 2 is an enlarged side view of the clothes line separating element, parts being removed for convenience of illustration.

Fig. 3 is a cross sectional view of Fig. 2 on line 3—3.

Fig. 4 is an enlarged plan view of the twisting and stretching means for the lines, parts being removed for convenience of illustration.

Fig. 5 is a side view of the clothes line structure, illustrating a modified separating element for the line.

Fig. 6 is an enlarged side view of the modified separating element shown in Fig. 6, parts being removed for convenience of illustration.

Fig. 7 is a sectional view taken on line 7—7 in Fig. 6.

Fig. 8 is a sectional view taken on line 8—8 in Fig. 6.

The clothes line structure consists of a major line 1, said line being untwisted and having its ends rigidly supported. One end of said line is secured to a bracket 2, that is attached to a rigid support 3, while the other end of said line 1 is secured to a cylindrical tube 4, said tube being rotatably carried by a channel member 5 as 55

shown in Fig. 4. One end of said tube 4 rotates in a leg 50 of the channel member 5 through which the tube extends, while the other end of said tube has a head 6 through which a pin 7 engages, said pin being inserted in the other leg of the channel member and fastened by a cotter key 8. To tighten the line the tube 4 is pulled outwardly a predetermined distance to permit the last said end of the tube to clear a protrusion 9 that is carried by the second said leg of the channel member and engages in an aperture 10 through said head, and then said tube is turned by a handle 11 that engages diametrically through openings 51 in the tube, and may be removed when tightening of the lines has been accomplished. When the line is tightened sufficiently, the tube is released and by action of spring 12 that engages on the pin 7, the protrusion 9 will enter an aperture 10 to retain the tube against rotation. The channel member 5 is rotatably secured to a bracket element 13 through the medium of a bolt 14, said member 5 being retained against rotation by a locking device 15 that engages through an opening 15' in the web 52 of the channel member and through an opening 53 in the bracket, said bracket 13 being attached to a rigid support 13'.

Twisted about the major line 1 and running from end to end thereof is a pair of minor lines 16, said minor lines having one set of corresponding ends secured to the bracket 2, while their other ends are adjustably secured to a similar tube 4 as previously described, said tubes being rotated to tighten their respective line in like manner to that of the major line. The minor lines are twisted about the major line by the rotation of the channel element 5, which is retained against rotation by the insertion of the locking device 15, and from time to time as the lines become slack, the same may be tightened by the rotatable tubes 4.

The major line may be of a galvanized single strand wire, while the minor lines may be of flexible nature such as fabric cords, or cables consisting of a plurality of fine metallic strands to provide free and repeated bending thereof as the minor lines are twisted and untwisted in their function of securing pieces of laundry to the major line without the use of clothes pins.

To open the minor lines for providing an opening for the insertion of laundry and to remove the laundry from the major line, there is provided a separating element that is moved in a selected direction for its respective purpose.

The said separating element consists of a rectangular frame 17 having a handle 18 secured to one of its corners, and depending downwardly therefrom. Rotatable in said rectangular frame is an annular ring-like element 19 that is carried by rollers 20 positioned adjacent the corners

of the rectangular frame. To avoid lateral or endwise movement of the ring in the frame is through the medium of a depressed plate 21 for each side thereof, said plates, each having a centrally disposed opening 54 as accessible means to the annular ring 19. The rollers are mounted upon sleeves 22 that extend from one plate to the other plate and being secured thereto by screws 22', said screws extending through openings 55 in the plates and threadedly engaging in their respective ends of the sleeves 22, whereby the plates are clamped to the rectangular frame as carrying means for the rollers and furthermore to avoid lateral movement of the annular ring 19.

Carried by the annular ring 19 is a pair of grooved rollers 23 and 24, spaced apart and adapted to revolve about the center axis of the annular ring as carried thereby at the time of twisting and untwisting the minor lines as engaged thereby. The rollers are rotatably mounted on a shaft 25, ends of each shaft engaging in the annular ring tightly to avoid displacement thereof during operation of the separating element. To diametrically retain the rollers within the ring, spacers 26 are mounted on the shaft and positioned on the sides of the rollers.

The major line slidably engages through a tube 27 that is axially carried in the ring 19 by a pair of discs 28 and 29 that are clamped to the sides of the ring by bolts 30 extending through the discs as shown in Figs. 2 and 3. The tube 27 is pressed tightly in a centrally disposed aperture 56 of disc 28, and extending loosely into an aperture 57 of the other disc 29 to provide easy separation of the discs from the annular ring. To retain the periphery of the discs in registry with that of the ring is through the medium of an annular flange 31 extending inwardly from each disc and engaging the ring internally. Each disc has a pair of elongated slots 32 through which the minor lines extend as engaged by the rollers.

To operate the separating element, the same is moved by gripping the handle, during which time the ring element is rotated as the rollers follow the twists of the minor lines to untwist the lines forwardly of the line of movement of said separating element for removing laundry from the lines, while rearwardly with respect to the above line of movement, the minor lines are twisted about the major line after the laundry has been inserted between the major and the minor lines. It will be understood that the rollers are sufficiently spaced apart to provide separation of the minor lines from the major line at the time of securing or removing laundry therefrom.

Figs. 5 to 8, inclusive, illustrate a modified separating element for a pair of twisted lines 33 and 34, the ends of which are secured rigidly in the same manner as previously described for the minor and major lines, and components thereof are identified by the same reference characters.

It will be seen that the modified arrangement consists of a rectangular frame 35, having a circular depressed plate secured to each side thereof by bolts 36 extending through openings 58 in the plates and having nuts 59 to clamp the rectangular frame therebetween. The depressed portion 37 of the plate is means to retain the plates in registry with respect to an opening 60 provided therein centrally while the flange portion 38 of

the plate lies upon its respective edge of the frame and extends therefrom to provide a stop to avoid slipping of an operator's hand from the rectangular frame when the same is gripped for movement of the separating element along said pair of lines for opening and closing the twists thereof for the purpose above described. In this instance of movement, the force applied to move the element is applied at two points, which are diametrically opposite each other, in other words, the thumb engages one side of the rectangular frame between the flanges, while the fingers engage an opposite side thereof. The bolts 36 are positioned in their respective corner of the frame, and have mounted thereon flanged rollers 39 as rotatable receiving means for an annular ring 40, said ring having plates 41 to close its sides thereof. Positioned in the ring and carried thereby is a roller carrying block comprised of a base portion 42 and a pair of legs 43 extending oppositely from the base portion, each pair of legs to provide a bearing for its respective grooved roller 44 that are adapted to rotate as carried by their respective shafts 45 extending therethrough and through the legs as shown in Figs. 6, 7, and 8. The roller carrying block is secured in the ring 40 by a pair of bolts 46 that extend through the plates and through said base portion 42 and having nuts 61 whereby the ring and block element are clamped by the plates similarly as described for Fig. 3. The discs or plates 41 are apertured as at 47 as threading means for the lines through the said internally rotatable ring 40.

While I have shown a pair of minor lines twisted about a major line, the same may be increased in the number of lines if so desired without departing from the spirit of my invention, and furthermore the exact details and proportion thereof may be varied as lie within the scope of the appended claim.

Having fully described my invention what I claim as new and desire to secure by Letters Patent is:

In a separating element of the class described, for use with a plurality of twisted lines, a rectangular frame, means on the frame to manipulate the element, a pair of depressed plates for each side of the frame, and rollers rotatably mounted internally of the frame adjacent the respective corners of the frame, an inner ring-like element rotatably carried by the rollers, said ring-like element having connected plates to close each side thereof, and grooved pulleys mounted on shafts between the plates each adapted to receive its respective line as opening means for the twists of the line.

MARY E. SEYMOUR.
